Patented June 19, 1917.

WITNESS:

S. J. Taylor

INVENTOR
Anton C. Eggers,

BY
Ernest Hopkinson
HIS ATTORNEY

UNITED STATES PATENT OFFICE.

ANTON C. EGGERS, OF BROOKLYN, NEW YORK, ASSIGNOR TO THE GOODYEAR'S INDIA RUBBER GLOVE MANUFACTURING COMPANY, A CORPORATION OF CONNECTICUT.

PNEUMATIC CUSHION.

1,230,690.

Specification of Letters Patent. Patented June 19, 1917.

Application filed August 10, 1915. Serial No. 44,816.

To all whom it may concern:

Be it known that I, ANTON C. EGGERS, a citizen of the United States, residing in Brooklyn, county of Kings, and State of New York, have invented certain new and useful Improvements in Pneumatic Cushions, of which the following is a full, clear, and exact description.

This invention relates to pneumatic cushions, especially adapted for use by persons suffering from inguinal hernia, Bright's disease, or other ailments which produce inflammation or cause sensitiveness in the lumbar regions. Cushions made according to this invention are also adapted for the use of persons afflicted with disorders which cause such frequent urination that it is impracticable to disturb the patient's sitting position.

It is the object of this invention to provide a cushion constructed in such a way that when in use there is no contact with the inflamed or sensitive parts of the body of the user. A further object of this invention is to provide a cushion formed so that the patient may without discomfort or substantial change of position accomplish the frequent urination necessitated by such disorders.

I accomplish my object by forming a cushion having its main load supporting or seat portion of approximately horse-shoe shape with a restricted connecting portion joining the ends and adapted to prevent spreading of the sides by the internal fluid pressure or by the weight of the person seated thereon.

For a clearer understanding of my invention reference is made to the following description and to the accompanying drawings in which:

The figure is a plan view of a pneumatic cushion made according to this invention.

The preferred construction of my cushion is substantially as follows:

A plurality of pieces of rubberized fabric are joined by cement about their margins *a* and *b* to form an air-tight bag *c*, the usual valve *v* being provided to permit inflation.

The method of building up the structure is that ordinarily employed in the manufacture of hollow rubber goods and forms no part of my invention, the novel feature being the formation of the front part thereof so that it does not contact with the sensitive

parts of the body of the user, or form an obstruction in case it is necessary for him to urinate. This I accomplish by restricting the front portion to a relatively small arched connecting element *d* between the sides of the cushion *c* and spanning the space therebetween. The part *d* is arched outwardly to avoid the sensitive parts of the body and defines an enlargement of the central opening through the cushion. While it may be formed of any stiff substantially inflexible material, I have found stiff rubber tubing to be well adapted to this use, principally because it can be firmly joined to the material of the cushion at the points *g* and *h* either by cement or vulcanization.

The part *d* is adapted to project beyond the edge of a chair seat upon which the cushion may be placed, and forms a forwardly extending reduced portion of the central opening. To permit urination by the occupant the part *d* may be bent down out of the horizontal plane in which it normally lies. Little effort is required to accomplish this as the forwardly projecting central portion provides leverage to permit turning.

To provide sufficient supporting area to the cushion I provide the inwardly projecting parts *e* and *f*. These make the cushion much more comfortable for the occupant, without, however, interfering with the functions mentioned above.

A cushion built according to this invention permits the use of a portable urinal without any necessity for disturbing the patient's sitting position, a downward bending or turning of the part *d* of the cushion over the edge of the chair seat upon which it is placed removing all obstruction in front of the occupant's body.

While I have described this cushion as formed of rubberized fabric, the various parts of which are joined by cement, I do not limit myself to that construction, as I may equally well form the article of sheet or molded rubber, and I wish to be understood as including such a construction as in the scope of my invention.

What I claim as my invention is:

1. A pneumatic cushion comprising an inflatable load supporting seat part having a comparatively large opening through the interior thereof, and a restricted part of substantially inflexible material spanning

103

110

the front to overcome spreading and to give continuity to the seat, said restricted part being directed forwardly toward its center to provide leverage therefor to permit said part to be turned downwardly when the seat is supporting the load.

2. A pneumatic cushion comprising a horse-shoe shaped seat portion of limp flexible material and an arched relatively stiff 10 connecting element of reduced cross-section connecting the ends thereof and adapted to retain said seat portion in its normal form under internal fluid pressure.

3. A pneumatic cushion comprising a 15 horse-shoe shaped seat portion of limp flexible material and an arched relatively stiff

element of relatively smaller cross-sectional area connecting the ends of said seat portion, said connecting element being adapted to be displaced upwardly or downwardly 20 out of the central plane of said seat portion.

4. A pneumatic cushion consisting of an oval shaped air member, that part of said member forming the front of the cushion being uninflatable and of relatively smaller 25 area in cross-section than the parts constituting the sides and rear and forming a forwardly extending reduced portion of the central opening through the cushion.

Signed at Brooklyn, New York, this 5th 30 day of August, 1915.

ANTON C. EGGERS.
